UNITED STATES PATENT OFFICE.

HENRI JOSEPH BOUVIER, OF GRENOBLE, FRANCE.

GOVERNOR.

SPECIFICATION forming part of Letters Patent No. 715,961, dated December 16, 1902.

Application filed April 21, 1902. Serial No. 104,025. (No model.)

To all whom it may concern:

Be it known that I, HENRI JOSEPH BOUVIER, engine-builder, a citizen of the French Republic, residing at Grenoble, department 5 of Isère, France, (post-office address "Chemin du Polygone,") have invented certain new and useful Improvements in Governors, of which the following is a specification.

My invention relates to a governing device 10 which is applicable to all kinds of prime movers, and especially to hydraulic motors.

While in steam - engines it is possible to cause the governor to act directly on the valve-gear, it becomes necessary in the case of hydraulic motors to arrange between the governor and the sluice some kind of intermediate transmission-gear, because the sluice requires for its operation the exertion of a certain amount of power, which cannot be obtained from the governor. In the governing devices hitherto known the governor acts by means of a coupling on a gearing actuated by the hydraulic motor, so as to open or close the valve of an auxiliary motor operating the 25 sluice directly. The sluice mechanism is thus connected to the governor only through the medium of an auxiliary motor, which does not necessarily stop the sluice in the position of equilibrium—that is, the position

30 corresponding to the equality between the motive power and load. To obtain a good regulation of speed and avoid the oscillation resulting from the latter mode of governing, it is therefore necessary that the governor 35 should not act by the release of a mechanism, as in the case just considered, but should influence in a continuous and direct manner the sluice mechanism through the medium of relays supplying the whole of the

40 power necessary for operating the sluice. If in this case the variation of speed is not to exceed five per cent., for instance, any suitable governor may be used and the same caused to have a controlling action on the 45 part of its stroke that corresponds to a variation of five per cent. By means of suitable gearing the sluice mechanism can be actuated by the movement of the governor, the governing being effected in such a manner 50 that the sluice is fully open when the governor occupies its lowest position and completely closed when the governor has reached

its highest position. By suitably calculating the proportions of the fly-wheels, so as to eliminate the influence of other causes of irregularity, the variation of speed will never exceed five per cent.

The object of my invention is a governing device which fulfils all these requirements. In the said apparatus the governor acts on 60 an outlet discharging a liquid forced by a rotary pump driven at a practically constant speed, the variation of the area of the outlet causing variations of the pressure of the liquid delivered, which pressure acts on a piston 65 whose motion is opposed by springs or other suitable means. For the whole range of the variation of the pressure this piston compresses the springs by a certain amount, thereby accomplishing a certain travel, while 70 each of its successive positions corresponds to a certain determined pressure in the apparatus. This travel of the piston I utilize for actuating directly the hydraulic motor's 75 sluice when it does not require the exertion of a large amount of power of its movement. If, on the contrary, the operation of the sluice requires a large amount of power, I cause the said piston to actuate the operating-valve of 80 an auxiliary motor connected directly to the sluice.

In order that my invention may be clearly understood, I will now proceed to describe the same more fully, with reference to the accompanying drawings, in which— 85

Figure 1 is an elevation of my apparatus, showing in section the auxiliary motor connected thereto. Fig. 2 is a plan of Fig. 1. Fig. 3 is a section through line A B of Fig. 1; and Fig. 4 is a horizontal section, on a 90 larger scale, through line C D of Fig. 3.

a is the governor, the spindle of which is supported by a bed-plate b. The sleeve of this governor is connected to one end of a rod c, fulcrumed in d to the bed-plate b and 95 operating at its other end a lever e, controlling through the medium of a crank f the plug g of a cock, which will be further described. This cock enables a rotary pump driven by a pulley h to draw water from a 100 tank j and to force it back thereinto, k being the suction-pipe. The water raised by the vanes i is forced into a pressure-chamber m, in which is provided a cylindrical casing

n, having two openings *o o'*, arranged diametrically opposite each other. In this casing turns the plug *g*, which is likewise provided with two openings *p p'*. The inside part of the plug opens into the tank *j* and provides openings of variable area for the return of the water into the tank.

To the chamber *m* is attached a pipe *q*, connected to the end of a cylinder *r*, containing a piston *s*, working against the action of a system of springs *t*. The rod *s'* of the piston *s* carries the valve 1, operating the auxiliary motor, which is constructed as follows:

In a chamber *u* moves a hollow piston *v*, provided with a port *w* and controlling, by means of a rod *x*, the lever *y*, which operates the sluice. The piston *v* has attached to it a differential piston *z*, inside which moves the rod of the piston *s*, carrying the valve 1, which closes the port *w*. The differential piston *z* is provided at 2 with an opening for the outlet of pressure-water supplied by a pipe 3 to the annular space 4, comprised between the chamber *u* and the piston *z v*.

As will be hereinafter explained, this piston follows exactly all the movements of its valve.

The operation of my apparatus is as follows: The pump delivering a practically constant quantity of water forces it into the pressure-chamber *m*. Part of this water falls back into the tank *j* as it flows through the openings of the cock. The pressure existing in the chamber *m* is transmitted to the piston *s* of cylinder *r*. If the plug *g* is rotated by the action of the governor, the resulting variations of the area of the return flow of the water will cause corresponding variations of pressure in the chamber *m*, and consequently on the piston *s*, for the pump having a practically constant delivery the pressure of the water delivered by it will become greater as the return-flow area becomes more throttled. The governor *a* therefore cause a direct variation of the pressure on the piston *s*, thereby causing it to exert a variable effort on the spring *t*, which becomes more or less compressed and insures the piston occupying a position determined by that of the governor. Let us, for instance, presume that the pressure of the delivery is increasing. The pressure on piston *s* increases, and the piston compressing the spring *t* moves toward the right, Fig. 1, while the valve 1 moves likewise to the right, and the port *w* establishes a communication between the port 2 of piston *z* and the chamber 5, comprised between the right-hand face of the piston *v* and the bottom of the chamber *u*. The water supplied by the pipe 3 will exert its pressure only on the left-hand annular face of the piston *v*. This pressure causes the piston *v* to move to the right and to impart to the sluice the required amount of motion. If, on the contrary, the piston *s* tends to move toward the left in consequence of a decrease of pressure, the valve 1 moves likewise toward the left, and the communication between the water under

pressure flowing through the pipe 3 and the port 2 is interrupted; but the space 6 and the port *w* form a communication between the annular space 4 and the chamber 5. The same pressure is exerted on both sides of the piston *v*; but while on the side corresponding to chamber 5 the pressure is exerted on the whole of the piston area it is on the side corresponding to the space 4 exerted only an annular area. Under these conditions the pressure in 5 being the greater will cause the piston to move toward the left and move the sluice in a direction opposite to that of the previous case. Thus with this arrangement the governor actuates the sluice-gear through the medium of the hereinbefore-described mechanism, the power exerted being only that which is necessary to turn the plug *g*. To sum up: Let it be presumed, as in the preamble of this specification, that the variation of speed is not to exceed five percent. When the speed increases, the governor gradually decreases the cross-sectional area of the passage of liquid through the valve, and vice versa if the speed decreases. The pump revolving at a practically constant speed forces exactly, or nearly so, the quantity of water delivered by it is constant. The pressure of the forced liquid increases as the area of the outlet decreases for a variation of speed of five per cent. The pressure of delivery may, for instance, vary from zero to ten kilograms per square centimeter. This pressure is exerted on the piston which compresses the springs that are so adjusted that for a range of variation of pressure from zero to ten kilograms the total piston-stroke is equal to the total lift of the sluice. The piston actuates directly the valve of an auxiliary motor operating the sluice and driven by liquid-pressure, this pressure being that due to the head of the water driving the hydraulic motor, or the pressure may be produced by an accumulator-force-pump. This auxiliary motor follows exactly the movements of its valve, and consequently that of the piston connected thereto. To each position of the governor comprised within the given range of variation— five per cent, for instance—corresponds a certain pressure in the pipe *q*, and consequently a definite compression of the springs, insuring an exact position of the piston and through the medium of the auxiliary motor a definite position of the sluice or gate of the hydraulic motor.

The hereinbefore-described arrangement by means of which the governor controls the sluice through the agency of a gradually-increasing pressure working against the action of opposing springs has the further advantage that it may be applied not only to one, but also to several hydraulic motors. In this case only one pressure-generating apparatus and governor are used, the said apparatus being driven by the machinery of the plant the working speed of which has to be controlled. Each hydraulic motor is in this case

provided with an auxiliary motor, with its piston and counterbalancing-springs, the liquid under pressure being supplied to each auxiliary motor by the aforesaid single pressure-generating apparatus by means of a common main connected to the pressure-chamber *m*. All the sluices are thus worked simultaneously. The stroke of each sluice may, however, be separately regulated by a suitable adjustment of the auxiliary motor operating it.

The hereinbefore-described arrangement may also be applied to a group of steam-engines. In this case, the effort to be exerted being relatively small, the auxiliary motors may be dispensed with and the pistons *s* connected directly to the cut-off gear.

The hereinbefore-described mode of governing the speed of a series of motors by means of a single governor is of special advantage for central electric-power stations, as it has been found out that independent governors controlling motors connected together were in themselves a cause of considerable speed fluctuations.

Having now particularly described and ascertained the nature of my said invention and in what manner the same is to be performed, I declare that what I claim is—

1. In a speed-controlling device for motors, the combination with the motor, of a centrifugal governor actuated thereby, a rotary pump actuated by the motor and communicating with a liquid-supply, a pressure-chamber in communication with said pump and adapted to receive the liquid from said supply through the medium of said pump, means connected with said governor and arranged in the said pressure-chamber for regulating the supply of fluid thereto, a cylinder, means

for conducting liquid from said pressure-chamber to said cylinder, a piston operating in said cylinder, and an auxiliary motor connected to said piston.

2. In a speed-controlling device for hydraulic steam, and other motors, a centrifugal governor and a water-circulating pump both operated from the motor, a piston in communication with a pressure-chamber behind the pump and means for operating the sluice, consisting of an auxiliary motor connected with the piston, substantially as described.

3. In a speed-controlling device for motors, the combination with sluice mechanism and the motor, of a centrifugal governor actuated thereby, a water-circulating pump operated from the motor, a pressure-chamber adapted to be supplied with liquid by the said pump, means for regulating the supply of liquid to said chamber, a piston in communication with said chamber and adapted to be operated by the supply of pressure thereto, and means connected to said piston for operating the said sluice mechanism.

4. In a speed-controlling device for motors, a governor, a pressure-chamber, means for supplying liquid to said chamber, means connected with the governor and adapted to regulate the supply of liquid to said chamber, a piston communicating with said chamber and operated by the pressure therefrom, and an auxiliary motor actuated by said piston.

In testimony whereof I have hereunto set my hand in presence of two subscribing witnesses.

HENRI JOSEPH BOUVIER.
